UNITED STATES PATENT OFFICE.

THOMAS J. MARTIN AND JEAN MULLER MARTIN, OF NEW YORK, N. Y.

HAIRDRESSING APPLIANCE.

Application filed November 17, 1923. Serial No. 675,423.

This invention relates to hair dressing appliances of the curling-iron variety that are heated by electrical energy. The particular device here considered is designed to offer a dual pronged arrangement especially applicable for producing an undulating or Marcel wave.

The objects of this improvement are to construct an electrically heated article that may be handled with safety by arranging the current connections between the service line and an electrical resistance coil in a manner that will prevent excessive heat from passing into a handle portion. Also, in providing an appliance that will permit of winding the hair in a figure-8 form about a pronged element and allowing the withdrawal of the said element without disturbing the figure-8 arrangement which is afterwards intentionally disturbed to produce the ultimate effect. A further object is, to devise an assembly that may be put together readily and avoid complications in manufacture with a view to lessening the costs attending the production of devices of this kind which are intended to reach the purchaser at a low retail charge.

Other advantages may be noted in the following description, referring to the accompanying drawing which is part of this application.

Fig. 1 is a broken sectional view of the device;

Fig. 2 an enlarged view of the wire splicing here adapted;

Fig. 3 a section on line 3—3 of Fig. 1;

Fig. 4 a fragmentary view of the hair-winding method;

Fig. 5 a modified form for housing the spliced portion.

Similar characters of reference apply to like parts throughout the several views.

A handle H is centrally drilled to provide a major bore h and a minor bore h' for admitting therethrough a service cord C of the duplex variety having the negative and positive wire c and c'. The handle H widens into a rectangular pad H' to coincide with a block B to which the said handle is attached by means of the screws s—s. The block B is recessed to offer a cavity or chamber b for accomodating the bulky splicing between an electrical heating means, to be later described, and the aforesaid cord C.

Tightly embedded in the block B are a pair of tubular prongs P whose tines may

be of shorter lengths for such as bobbed hair, this feature is indicated in dotted lines as p' on Fig. 1. The said prongs being hollow are spun at the outer ends to provide the smooth and blunt points T which readily enter the hair and allow of easy withdrawal therefrom. Within the prongs an electrical resistance wire 1 is inserted the entire length of the prongs in order to provide an even heat throughout the area over which the hair is wound. The resistance 1 is connected, by the aforesaid splicing, to the cord C with which it forms a continuous circuit that leads from the wire c, into and out of one tine, crosses through the chamber b and similarly enters the other tine thence out through wire c', as is clearly shown in Figs. 1 and 2.

Fig. 2 shows in detail the connection adapted here for electrically stepping from the heat of the resistance means, or coiled wire to the normal service cord, for stopping the excessive heat in the said resistance wire from passing beyond the chamber b. This step is attained by wrapping together the naked ends of the resistance wire and the wires c and c' with a fine copper wire 2. Over this jointure is wound a covering of asbestos yarn 3 and the splicing is in turn taped compactly with an adhesive and heat resisting braid 4 which is continued up the cord C for a suitable distance so as to provide a purposeful thickening of the cord C in the bore h that will resist any inordinate pull upon the said cord, by virtue of the shoulder K, from disturbing the splicing J which is finally embedded in a heat resisting mass within the aforesaid chamber b.

Fig. 4 illustrates how the hair is placed about the prongs and pushed along same until the desired amount is laced thereon when the current is turned on for a period of time after which the device is removed and the strands of hair unfolded by hand to arrange the desired effect.

Fig. 5 is a modified form of housing for the spliced portion described above, and consists of a vertically split bakelite block B' oppositely cored at b' and encased in a shell S that embraces the handle H to which it is securely attached by suitable screws or rivets s' located at either side of the bore h. The bakelite element in this modified form leaves the asbestos yarn an unnecessary precaution for guarding against the high temperature that occasions the

adaptation of the said yarn in the first described method. The said Fig. 5 shows an alternative method of providing individual tips T' for acquiring the blunt ends of the 5 prongs, here indicated as P'.

Having described this invention what is desired to protect by Letters Patent is:

1. A hair dressing appliance having, a counterbored handle attachable to and registering with a chambered block, said block forming a spacing base between dual prongs and the said handle, the block aforesaid adapted to contain heat resisting material in which is embedded current conducting 15 wires that pass from said handle and the prongs aforesaid.

2. In a hair dressing appliance the combination of, a counterbored handle and tubular prongs, electric wiring means for heating the said prongs, a bifurcated spliced jointure for retarding the heat of said means from passing back into the handle portion, an intermediate chamber for housing the bifurcated spliced union between the 20 handle aforesaid and the prongs, and a heat resisting material embedding the bifurcated jointure within the chamber aforesaid.

3. A hair dressing appliance having, an intermediate block member for uniting a 25 pronged portion with a handle portion,

chambered means in said block for maintaining in bifurcated relationship the jointures connecting a service wire to a heating element.

4. A hair dressing appliance comprising 35 a pronged portion and a handle portion having, an electric element and a heating element bifurcated and bound together by a metallic medium of less resistance than either element aforesaid, heat resisting 40 windings about the jointures so formed, said jointures disposed within an outer covering that is extended beyond the jointures to increase the thickness of said service element to a diameter that exceeds a reduced 45 bore in the aforesaid handle portion.

5. In a hair dressing appliance the combination of, a handle portion, a pronged portion, an intermediate element of heat resisting properties arranged to provide bifurcating grooves that function as leads to dual passages in the aforesaid pronged portion and to a singular passage of varying 50 diameter piercing the aforesaid handle portion.

In testimony whereof we affix our signatures.

THOMAS J. MARTIN.
JEAN MULLER MARTIN.
